UNITED STATES PATENT OFFICE.

DAVID W. HAWKSWORTH, OF DETROIT, MICHIGAN, ASSIGNOR TO HUTCHINS CAR ROOFING COMPANY, OF DETROIT, MICHIGAN, A CORPORATION OF MICHIGAN.

CAR-ROOF.

1,089,554.

Specification of Letters Patent. Patented Mar. 10, 1914.

Application filed December 2, 1910. Serial No. 595,256.

To all whom it may concern:

Be it known that I, DAVID W. HAWKSWORTH, a citizen of the United States of America, residing at Detroit, in the county of Wayne and State of Michigan, have invented certain new and useful Improvements in Car-Roofs, of which the following is a specification, reference being had thereto in to the accompanying drawings.

0 The invention relates to car-roofs, and more particularly to the means employed for securing the carlines to the side plates, more fully hereinafter set forth.

In the drawings,—Figure 1 is a cross section through the side plate of a car showing a portion of the carline and the attaching means therefor; and Fig. 2 is a perspective view of the carline securing bracket.

It is usual in the construction of cars to employ plates at the top of the sides and to connect the carlines to said plates. Where metallic carlines are used these are generally secured by passing over the plates and flanging downward over the outer faces thereof. 25 With the present construction the metallic carlines terminate at the inner side of the plates to which they are secured by metallic brackets.

As shown, A are carlines of an inverted channel section having laterally extending flanges B; C is a bracket having a flange D bearing against the inner face of the plate E, and a portion F which fits within the channel of the carline being secured to the 35. web thereof by rivets F'.

G are flanges on opposite sides of the bracket forming bearings for the flanges B of the carline.

H is a portion extending outward over

the top of the plate, and I is a depending lug on the portion H which engages a bore in the plate and is apertured to receive a vertical securing bolt J. The flanges D are secured to the plate by bolts K extending through lateral bores in the plate and preferably also through the facia L.

With the construction as described, the bracket C is secured to the plate by the bolts J and K which extend in transverse directions mutually strengthening the plate 50 against splitting stresses. The lug I engaging a counterbore in the plate forms a hook for positively tying the bracket thereto, while the flange D forms an abutment for limiting outward movement. Thus the carline is securely attached to the plate with the saving of metal usually necessary to pass over the plate and forming the flange at the outer face thereof.

What I claim as my invention is:

In a car roof, the combination with a plate, of a metallic carline of inverted channel section terminating at the inner face of said plate; a bracket having a portion fitting within said channel and secured to the web 65 portion thereof, said bracket also having flanged portions bearing against the top and inner side of the plate, bolts for securing said flanges passing transversely through said plate, and an apertured lug surrounding one of said bolts and engaging a counterbore in the plate.

In testimony whereof I affix my signature in presence of two witnesses.

DAVID W. HAWKSWORTH.

Witnesses:

JAMES P. BARRY,
ADELAIDE I. ADAMS.
